DESIGN.

R. H. WATERS.

VEHICLE TIRE.

APPLICATION FILED NOV. 22, 1920.

57,878.

Patented May 10, 1921.

FIG II

INVENTOR
Reginald H. Waters.

UNITED STATES PATENT OFFICE.

REGINALD H. WATERS, OF AKRON, OHIO, ASSIGNOR TO KELLEY-SPRINGFIELD TIRE COMPANY, OF NEW YORK, N. Y., A CORPORATION OF NEW JERSEY.

DESIGN FOR A VEHICLE-TIRE.

57,878.

Specification for Design. Patented May 10, 1921.

Application filed November 22, 1920. Serial No. 425,925. Term of patent 14 years.

To all whom it may concern:

Be it known that I, REGINALD H. WATERS, a citizen of the United States, residing at Akron, county of Summit, and State of Ohio, have invented a new, original, and ornamental Design for a Vehicle-Tire, More Particularly Known as a Solid Resilient Truck-Tire, of which the following is a specification, reference being had to the accompanying drawing, forming a part thereof.

Figure I— is a partially completed perspective view of a tire, showing my new design. "A" designates a series of opposed notches radial of the tire, in spaced and staggered relation and bisected substantially at the median plane of the tire by an annular groove "B".

Fig. II— is a cross-sectional view through the line 2—2 of Fig. I showing the cross-sectional form of the tire body and particularly illustrating the progressive increase in depth of the notches "A" outwardly of their central terminus. "C" is any type of rim on which such a tire may be mounted and is not an element of this design.

I claim:

The ornamental design for a vehicle tire as shown and described.

Signed at Akron, in the county of Summit, in the State of Ohio, this 19th day of November, 1920.

REGINALD H. WATERS.
